UNITED STATES PATENT OFFICE.

EMMET J. WARREN, OF DETROIT, MICHIGAN.

ODORLESS GARBAGE-RECEPACLE.

1,265,148.

Specification of Letters Patent.

Patented May 7, 1918.

Application filed April 16, 1917. Serial No. 162,432.

To all whom it may concern:

Be it known that I, EMMET J. WARREN, a citizen of the United States, residing at Detroit, in the county of Wayne, State of Michigan, have invented certain new and useful Improvements in Odorless Garbage-Receptacles; and I do hereby declare the following to be a full, clear, and exact description of the invention, such as will enable others skilled in the art to which it appertains to make and use the same.

This invention relates to improvements in garbage receptacles and particularly to odorless receptacles.

One object of the present invention is to provide a device of this character into which the garbage can be readily introduced and which will at the same time effectively prevent the escape of odors therefrom.

Another object is to provide a device of this character which is of such construction that the entire contents of the receptacle can be quickly and easily dumped by the collector without removing the cover.

Another object is to provide novel means for closing the garbage receiving opening which can be quickly and easily opened and closed. Other objects and advantages will be apparent from the following description when taken in connection with the accompanying drawing.

In the drawing:

Figure 1 is a side elevation of a garbage receptacle made in accordance with my invention.

Fig. 2 is a front elevation of the same.

Fig. 3 is a top plan view of the receptacle, the cover being removed.

Fig. 4 is a vertical transverse sectional view taken on the line 4—4 of Fig. 3.

Fig. 5 is a horizontal sectional view taken on the line 5—5 of Fig. 1.

Fig. 6 is a horizontal sectional view taken on the same line as that of Fig. 5, but showing the sliding plates in opened position.

Referring particularly to the accompanying drawing 10 represents a cylindrical receptacle formed from any suitable material, but preferably galvanized metal. In the upper end of the receptacle there is secured a downwardly and inwardly extending, inverted truncated cone member 11, the lower end of which forms the opening 12, through which the garbage is introduced into the receptacle. Mounted in the receptacle, on a level with the lower end of the cone member,

and at suitable distances at the sides of the opening therein, are two parallel guiding track members 13. Slidable in these track members are the semi-circular disks 14 and 14', the straight sides 15 of which are arranged to abut at a point midway of and below the said opening 12. Through one side of the receptacle, and preferably intermediate the corresponding ends of the tracks, there is disposed a bar 16, said bar being extended through an opening 17 in the side of the receptacle, and having its inner end secured to the adjacent disk 14. The outer end of the bar is turned upwardly, as shown at 18 to provide a handle by means of which the bar may be pushed in and pulled out, to slide the disk in the tracks. To the side of the receptacle, adjacent the before-mentioned end of one of the tracks, is secured an eye 19, while to the opposite side of the receptacle, and adjacent the other end of the other track there is secured a similar eye 20. To the disk 14 adjacent the first named eye 19 there is secured one end of a wire or other suitable cord 21, said cord being engaged through said eye and having its other end secured to the corresponding end of the other disk 14'. Secured to the other end of the disk 14' is one end of a second wire or cord 22, said cord being engaged through the other eye 20, and having its other end secured to the other end of the disk 14. Thus when the bar is pulled outwardly the disk 14 will also be pulled in that direction, and from beneath the opening 12, while the cord 22 will pull the disk 14' in the opposite direction, that is away from the disk 14, and from beneath the opening 12. Thus the opening will be uncovered to permit of the ready introduction of garbage into the receptacle. When the bar is pushed in the disk 14 will be pushed in and by reason of the pull of the cord 21 on the disk 14', said disk will be drawn to a point beneath the opening 12 and into abutting relation with the adjacent edge of the disk 14, thereby effectively closing the said opening.

A removable cover 23 is provided for the upper end of the receptacle, as clearly shown in the drawing.

In one side of the lower portion of the receptacle there is formed a slot 24, said slot extending to a distance equal to or slightly greater than one-half of the circumference of the body of the receptacle. Into this slot there is inserted a disk or pan member

25, said member being provided with a suitable handle by means of which the same may be quickly and easily slipped in and out of the slot. It will be noticed that the receptacle is without a bottom, except the disk 25, above referred to, whereby when the collector is to dump the receptacle, it is only necessary to lift the receptacle and rest the same on the side of the garbage wagon and 10 then remove the disk 25. The contents of the receptacle will immediately drop therefrom into the wagon.

Carried by the edge of the disk 25, is a loop or eye 26, which when the disk is in 15 proper position within the receptacle, registers with upper and lower similar eyes 27 carried by the receptacle above and below the slot. A pin 28 is removably disposed in these registering eyes to hold the disk from 20 accidental removal.

The ends of the wires or cords are attached to the disks by means of the hooks 29 carried by said disks, as clearly shown in the drawing.

25 What is claimed is:

1. An odorless garbage container including a receptacle, a frusto-conical wall in the upper end thereof, horizontal supporting trackways mounted below the lower end of the wall, oppositely sliding closure plates mounted in the trackways, eye members car-

ried by the inner face of the wall of the receptacle at diametrically opposite points and adjacent the ends of the said trackways, and cords connected at their ends to the corresponding ends of the plates and having their intermediate portions engaged through said eye members. 35

2. An odorless garbage container including a receptacle, an inverted frusto-conical wall 40 in the upper end thereof, horizontal parallel and transversely extending trackways mounted within the receptacle and below the smaller end of the said wall, oppositely movable disks mounted for sliding movement in the trackways, immediately beneath the smaller end of the frusto-conical wall, eye members secured to the wall of the receptacle adjacent one end of each of the trackways, and at diametrically opposite points with respect to the receptacle, and cords disposed slidably through said eye members, and each cord having one end secured to one end of one of the disks, and the other end secured to the corresponding end of the other disk. 45

In testimony whereof, I affix my signature in the presence of two witnesses.

EMMET J. WARREN.
